US00D811709S

(12) **United States Design Patent** (10) **Patent No.:** **US D811,709 S**
(45) **Date of Patent:** **** Mar. 6, 2018**

(54) **INSOLE**

(71) Applicant: **Protalus LLC**, West Linn, OR (US)
(72) Inventor: **Christopher Buck**, Portland, OR (US)
(73) Assignee: **Protalus LLC**, West Linn, OR (US)
(**) Term: **15 Years**
(21) Appl. No.: **29/549,955**

(22) Filed: **Dec. 29, 2015**

(51) LOC (11) Cl. **02-04**
(52) U.S. Cl. **D2/961**

(58) **Field of Classification Search**

(74) *Attorney, Agent, or Firm* — Mark T. Vogelbacker;
Eckert Seamans Cherin & Mellott, LLC

(57) **CLAIM**

The ornamental design for an insole, as shown and
described.

DESCRIPTION

FIG. 1 is a perspective view of a first embodiment of an
insole showing my new design;

FIG. 2 is another perspective view thereof;

FIG. 3 is a top plan view thereof;

FIG. 4 is a bottom plan view thereof;

FIG. 5 is a first side elevation view thereof;

FIG. 6 is an opposing second side elevation view thereof;

FIG. 7 is a rear elevation view thereof;

FIG. 8 is a front elevation view thereof;

FIG. 9 is a perspective view of a second embodiment of an
insole showing my new design;

FIG. 10 is another perspective view thereof;

FIG. 11 is a top plan view thereof;

FIG. 12 is a bottom plan view thereof;

FIG. 13 is a first side elevation view thereof;

FIG. 14 is an opposing second side elevation view thereof;

FIG. 15 is a rear elevation view thereof; and,

FIG. 16 is a front elevation view thereof.

The broken lines in the figures illustrate environmental
structure only and form no part of the claimed design.

The shaded surface area surrounding the broken lines is part
of the claimed design.

1 Claim, 8 Drawing Sheets
